CLAIM

The ornamental design for a computer display system or portion thereof showing a graphical user interface having a three dimensional appearance as shown and described.

DESCRIPTION

The FIGURE is a front view of a computer display system or portion thereof showing a graphical user interface having a three-dimensional appearance showing the claimed design. The peripheral broken lines in the FIGURE show the computer display system or portion thereof, and form no part of the claimed design.

The dashed broken lines in the FIGURE show a three dimensional environment within a field of view of the user and portions of the graphical user interface, that form no part of the claimed design.
